(57) **CLAIM**

The ornamental design for an LED bracket, as shown and described.

DESCRIPTION

FIG. 1 is a rear elevational view of the bracket;
FIG. 2 is a front elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a front perspective view of the bracket.
The features in broken lines are included for the purpose of showing portions of the LED bracket that form no part of the claimed design.
